(57) **CLAIM**

The ornamental design for a scooter, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a front view of a scooter;

FIG. 1.2 is a back view of the scooter;

FIG. 1.3 is a left view of the scooter;

FIG. 1.4 is a right view of the scooter;

FIG. 1.5 is a top view of the scooter;

FIG. 1.6 is a bottom view of the scooter;

FIG. 1.7 is a perspective view of the scooter; and

FIG. 1.8 is another perspective view of the scooter.

The portions of the scooter shown by coloring form no part of the claimed design.
